EZRA A. PHILLIPS, OF SMACKOVER, ARKANSAS, ASSIGNOR OF ONE-HALF TO WALTER
J. H. TOWN, OF SMACKOVER, ARKANSAS

TUBING DRAIN

Application filed May 31, 1930. Serial No. 458,475.

This invention relates to an attachment for the pipes of oil pumps and has as its primary object to provide an attachment by which the well pump pipe may be elevated without any liability of flooding the pump platform with oil and without incurring any waste of oil.

Another object of the invention is to provide, in combination with an oil well pipe, a novel valve means for venting the pipe when the same is elevated, so that the oil may flow out and not be carried up with the pipe in the elevation thereof.

This invention also consists in certain other features of construction and in the combination and arrangement of the several parts, to be hereinafter fully described, illustrated in the accompanying drawings, and specifically pointed out in the appended claims, it being understood of course that minor changes may be made so long as they fall within the scope of the claims.

In describing my invention in detail, reference will be had to the accompanying drawings, wherein like characters denote like or corresponding parts throughout the several views, and in which:—

Figure 1 is a view partly in section and partly in elevation illustrating the upper portion of the device embodying the invention.

Figure 2 is a similar view of the lower portion and constituting a continuation of Figure 1.

Figure 3 is a view in side elevation illustrating the manner in which one member of the device is anchored upon the well pipe.

Figure 4 is a horizontal sectional view on the line 4—4 of Figure 1 looking in the direction indicated by the arrows.

Figure 5 is a similar view on the line 5—5 of Figure 1.

Figure 6 is a similar view on the line 6—6 of Figure 1.

Figure 7 is a horizontal sectional view on the line 7—7 of Figure 2 looking in the direction indicated by the arrows.

In the drawings the numerals 1 and 2 indicate respectively upper and lower sections of the well tube and the lower and upper ends of these sections, respectively, are

threaded into a cylindrical valve casing 3 which is formed at diametrically opposite points with vertically extending bores 4 which open at their upper ends through the upper side of the said casing 3 and the casing is provided with ports 5 located a short distance above the lower end of each bore and communicating with the interior of the casing 3 at a point between the ends of the tubes 1 and 2. An annular head 6 is slidably fitted to the lower end of the tube 1 and normally held in a downward or lowered position through the medium of a compression spring 7 which is secured at its upper end to the tube 1 and bears at its lower end against the upper side of the head 6. The head is formed, in its outer periphery, with radial slots 8 which are located diametrically opposite each other and mounted in each of the bores 4 is a tubular valve 9, the bore of which is indicated by the numeral 10, and each of the valves is provided with a bore 11, and, above the bore 11 with spaced heads 12 and 13 and, the portion of each bore between the heads is seated in respective ones of the slots 8, the heads 12 and 13 engaging respectively, the under and upper sides of the head 6.

The under side of the head 12 of each valve is beveled as indicated by the numeral 14 to engage and seat upon a beveled seat 15 formed at the upper end of the bore 4 and it will be evident at this point that when the valve head 6 and the tubular valves 9 are in the positions shown in Figure 1, the valves will be closed or, more specifically, the valve 9 will close the port 5 and the wall of the bore 4 will close the port 11. For a purpose which will be made apparent, stems 16, four in number, are arranged in equidistantly spaced relation, for sliding movement in bores 17 formed in the casing 3 and the said stems 16 are symmetrically arranged with respect to the valves 9 as will be evident by reference to Figure 4. The upper ends of the stems are threaded, as indicated by the numeral 18, into threaded openings formed in the head 6 and the lower ends of the stems project below the lower end of the valve casing 3.

Mounted upon the well tube section 2 for rotative movement, is a swage 19. This swage

19 is of conical form and is provided with a cylindrical downward extension 20 and it will be observed by reference to Figure 1 that the upper side, or in other words, the end of 5 the swage which is of maximum diameter, is located a short distance below the projecting lower ends of the stems 16. A bead 21 surrounds the swage 19 substantially at the juncture of the conical and cylindrical portions thereof and the bead is formed with slot 22, and these slots slidably accommodate stems 23 which extend from the lower major 10 end of upwardly beveled heads 24 the inner side faces of which are inclined as indicated by the numeral 25 to correspond to the taper of the swage 19 and the outer sides of which are substantially plane and vertically disposed and which are formed with a series of teeth 26.

20. A barrel 27 of cylindrical form is mounted upon the tube section 2 below the cylindrical extension 20 of the swage 9. The lower ends of the stems 23 are turned outwardly at right angles as indicated by the numeral 28 and 25 project through vertical slots 29 formed in the said barrel 27 and in the normal positions assumed by the parts as shown in Figure 1, and these outwardly turned ends 28 engage at the upper ends of the slots 29. The tube section 30 2 is formed with an outstanding rib 30 and the bore of the barrel 27 is formed with longitudinal grooves 31 in which the lugs 30 may slidably engage in the upward movement of the section 2 of the well tube. At its lower 35 end the barrel 27 is interiorly increased in diameter as indicated by the numeral 32 and a compression spring 33 is arranged upon the tube section 2 and engages at its upper end in the enlargement 32 and bears against 40 the annular shoulder 34 which is provided by the formation of this enlargement. A collar 35 is slidably mounted upon the tube section 2 and is engaged by the lower end of the spring 33 and a similar collar 36 is fitted to 45 the tube section 2 below the collar 35 and a stud 37 upon the tube section 2 is engageable in a bayonet slot 38 formed in the lower edge of the collar 36. Outwardly bowed leaf springs 39 are secured at their upper ends in 50 any appropriate manner to the collar 33 and preferably these springs are three in number and are equidistantly spaced about the circumference of the two collars to which their ends are secured.

55. At this point it will be understood that the collar 36 is restrained against downward movement upon the tube section 2 and therefore, when an upward pull is exerted upon the tube section 1 and incidentally the tube section 2, the upward movement of the collar 36 will cause an expansion of the leaf springs 39 as the upward movement of the collar 35 is restrained by the compression spring 33. At the same time, the spring 33 is placed 60 under compression and therefore the swage

19 will be moved upwardly and likewise the heads 24 will be shifted radially outwardly as their inner sides ride upwardly over the upwardly inclined surface of the said swage and, finally, the teeth upon the outer faces of the heads 24 will engage the well lining and at this time the upper end of the swage will have engaged the lower ends of the stems 16 thus causing an upward displacement of the valve head 6 and upward displacement of the tubular valves 9 thus uncovering the valve seat 15 and exposing the ports 5 and 15.

What I claim is:

1. In a tubing drain of the class described, the combination with upper and lower sections of a well tube, of a cylindrical valve casing connecting the ends of said sections and provided with bores opening through its upper end, the said casing having ports communicating with the lower ends of the bores and with the interior of the casing, a tubular valve slidably mounted in each of said bores and open at its lower end, spaced heads upon the upper end of each valve, an annular head slidably fitting the upper tube section, means connecting the valves with the said annular head, a compression spring upon the said upper tube section bearing upon the said annular head and yieldably holding the same in lowered position and with the lower heads of the valves closing the upper ends of the respective bores, and the valves closing the ports, and an abutment movable with respect to the said valve casing and projecting below the same, the abutment being connected with the annular head and engageable by the swage upon upward movement of the same whereby to elevate the annular head and effect opening of the valves.

2. In a tubing drain of the class described, the combination with upper and lower sections of a well tube, of a cylindrical valve casing connecting the ends of said sections and provided with bores opening through its upper end, the said casing having ports communicating with the lower ends of the bores and with the interior of the casing, a tubular valve slidably mounted in each of said bores and open at its lower end, spaced heads upon the upper end of each valve, an annular head slidably fitting the upper tube section and provided with notches in its periphery, the portions of each valve, between the heads thereon, being engaged in a respective one of the notches, a compression spring upon the said upper tube section bearing upon the said annular head and yieldably holding the same in lowered position and with the lower heads of the valves closing the upper ends of the respective bores, and the valves closing the ports, and an abutment movable with respect to the said valve casing and projecting below the same, a swage upon the lower tube section, the abutment being connected with the annular head and engageable by the swage

upon upward movement of the same whereby to elevate the annular head and effect opening of the valves.

3. In a tubing drain of the class described, the combination with upper and lower sections of a well tube, of a cylindrical valve casting connecting the ends of said sections and provided with bores opening through its upper end, the said casing having ports communicating with the lower ends of the bores and with the interior of the casing, a tubular valve slidably mounted in each of said bores and open at its lower end, spaced heads upon the upper end of each valve, an annular head slidably fitting the upper tube section, means connecting the valves with the said annular head, a compression spring upon the said upper tube section bearing upon the said annular head and yieldably holding the same in lowered position and with the lower heads of the valves closing the upper ends of the respective bores, and the valves closing the ports, an abutment movable with respect to the said valve casing and projecting below the same, a swage upon the lower tube section, the abutment being connected with the annular head and engageable by the swage upon upward movement of the same whereby to elevate the annular head and effect opening of the valves, a collar fixed upon the lower tube section, a collar slidable upon said section above the first mentioned collar, bowed leaf springs connecting the collars, and a compression spring upon said lower section engaging the last mentioned collar and a cylinder slidably mounted upon said lower section and engaged by said spring, and coacting means upon the said cylinder and swage for effecting upward movement of the swage into engagement with the said abutment whereby to effect upward movement of the annular head.

4. In a tubing drain of the class described, the combination with upper and lower sections of a well tube, of a cylindrical valve casting connecting the ends of said sections and provided with bores opening through its upper end, the said casing having ports communicating with the lower ends of the bores and with the interior of the casing, a tubular valve slidably mounted in each of said bores and open at its lower end, spaced heads upon the upper end of each valve, an annular head slidably fitting the upper tube section, means connecting the valves with the said annular head, a compression spring upon the said upper tube section bearing upon the said annular head and yieldably holding the same in lowered position and with the lower heads of the valves closing the upper ends of the respective bores, and the valves closing the ports, an abutment movable with respect to the said valve casing and projecting below the same, a swage upon the lower tube section, the abutment being connected with the

annular head and engageable by the swage upon upward movement of the same whereby to elevate the annular head and effect opening of the valves, the said swage being of inverted conical form, a bead at the lower end of the swage having openings therein, wedge shaped heads each provided with a resilient stem extending through the openings in the bead, a cylinder slidably mounted upon the lower tube section, a collar fixed with respect to the lower tube section, a collar slidable upon said tube section above the last mentioned collar, bowed leaf springs connecting the collars, and a compression spring interposed between the said cylinder and the last mentioned collar.

In testimony whereof I affix my signature.
EZRA A. PHILLIPS.
